(57) **CLAIM**

The ornamental design for a rope light, as shown and described.

DESCRIPTION

FIG. 1 is a perspective view of the rope light of this invention. FIG. 2 is a side elevational view of a portion of the rope light, shown enlarged for clarity of illustration. The opposite side is a mirror image thereof; and,

FIG. 3 is an end view of the rope light of this invention. The view from the opposite end is a mirror image thereof. The portions of the rope light shown in broken lines form no part of the claimed design.
